UNITED STATES PATENT OFFICE.

RICHARD W. KOHL, OF CUMBERLAND, MARYLAND, ASSIGNOR TO JACIEL PERFUMERS, INC., OF NEW YORK, N. Y., A CORPORATION OF NEW YORK.

DESIGN FOR A BOTTLE OR LIKE CONTAINER.

Application filed December 14, 1927. Serial No. 24,474. Term of patent 14 years.

To all whom it may concern:

Be it known that I, RICHARD W. KOHL, a citizen of the United States of America, and a resident of the city of Cumberland, Cumberland County, State of Maryland, have invented a new, original, and ornamental Design for a Bottle or like Container, of which the following description in connection with the accompanying drawing is a specification.

Referring to the drawing:

Fig. 1 is a front elevation;

Fig. 2 is a side elevation;
Fig. 3 is a top plan view;
Fig. 4 is a bottom plan view; and
Fig. 5 is a longitudinal sectional view of a bottle or like container showing my new design.

I claim as my invention:

The ornamental design for a bottle or like container, substantially as shown and described.

RICHARD W. KOHL.
